3,301,221 WRITING DEVICES

Marcel Joseph von Arx, Montgeron, France, assignor to
Rotary Pen Corp., Kenilworth, N.J., a corporation of
New Jersey

Application Oct. 6, 1965, Ser. No. 497,594, which is a
continuation of application Ser. No. 235,763, Nov. 6,
1962. Divided and this application Apr. 11, 1966, Ser.
No. 541,850

Claims priority, application France, Dec. 22, 1961,
882,949, Patent 81,707
5 Claims. (Cl. 120—42.13)

This application is a division of copending application
Serial No. 497,594, filed October 6, 1965, now Patent No.
3,262,427 issued July 26, 1966, which in turn is a con-
tinuation of copending application Serial No. 235,763,
filed November 6, 1962, and entitled, "Ball Point Pens,"
and now abandoned.

The present invention relates to writing devices and
particularly to ball point pens of the multiple writing
unit type. Such pens are primarily used with writing
units charged with ink of different colors to give a quick
color-change in use but they may also be used with units
charged with the same ink so that when one unit is ex-
hausted, another can be brought quickly into operation.

In accordance with the present invention there is pro-
vided a ball point pen of the multiple writing unit type
and having for each writing unit a pusher which is spring-
biased from an engaged operative position towards the
retracted position, in which pen each pusher is provided
with a ramp adapted, when the pusher is advanced while
another pusher is engaged, to disengage the other pusher
and thereby cause it to be spring driven to its retracted
position.

In the operation of the pen each pusher is engaged
when the point of its writing unit projects in the writing
position at the end of the pen and is released for return
to its retracted position when another pusher is moved
from its own retracted position. Further movement of
the other pusher brings the new ball point into the writing
position.

In one preferred form of the pen each pusher consists
of a head part upon which the ramp is formed and a rod
part which passes through a helical spring which provides
the spring bias for the pusher. Mounted between the
pushers is a transversely displaceable ball which serves
to convey the disengaging reaction of the ramps from one
pusher to the other. Conveniently, the pushers are
formed with recesses which are penetrated by the ball
when the pushers are in the retracted position, said re-
cesses being bounded by the ramps. Conveniently, a
guide member for the pusher is mounted on the axis of
the pen and provides an abutment for restraining the
pushers in the engaged position. Advantageously the
guide member is grooved or slotted to accommodate the
ramps as the pushers are advanced.

Other features and advantages will become apparent
from the following description of preferred embodiments
of the invention; other embodiments, proportions and the
like may be used without departing from the spirit and
scope of the invention. In the accompanying drawings:

FIG. 1 is a part-sectional elevation of a preferred form
of the present invention designed for two writing units
with one ball point in the writing position and the other
retracted; and

FIG. 2 is a view similar to FIG. 1 with both ball points
retracted.

In all the figures, the same reference numerals signify
corresponding parts.

As illustrated in FIGS. 1 and 2, the pen has two writing
units *a* and *a*₁ arranged symmetrically about its longi-

2

tudinal axis. Obviously, the pen may be modified to have
more than two units, for example three spaced apart by
120°. The units are mounted in the body *b* of the pen,
which has a separately formed cap *c*.

5 Each unit is fitted to the rod part *d* of a pusher, slidably
carried in a fixed guide plug *e*, formed with internally
shouldered channels *e*₁ and fixed, for example, to the body
of the pen. Threaded over each rod part is a spring *f*
which bears against the base *g*₁ of a pusher head *g* and
against the shoulders of the channels *e*₁, by means of
which the pushers slide in the ring *e*.

Two cavities *h*, machined or moulded in the upper part
of the cap *c*, are adapted to receive the heads *g* of the
pushers which abut in the retracted position against the
15 shoulder *h*₁. These heads move along a median partition
i. The lower part of this partition forms a stop for the
forward portion *j* of the heads. The head *g* has a re-
cess *m*, bounded by a ramp portion *m*₁.

An aperture *n* is formed centrally through the forward
20 part of the partition *i* of the cap of the pen at the retracted
level of the notches *m* of the heads *g*. In the aperture
n is held a ball *o* which, as may be seen from the draw-
ings, is displaceable transversely to the axis of the pen.

The operation of the device of the present invention is
25 as follows:

Downward pressure exerted on the head *g* of the pusher
corresponding with the selected color is transmitted both
vertically to push the ball point forward, and transversely
to the axis of the pen so that the top *j* of the head of the
30 pusher engages under the partition *i*. When a pressure
is applied to the head *g* of the pusher, this head displaces
the ball *o* and engages in the operative position. The
ball is received in the recess *m* of the other pusher (FIG.
1). In order to release the engaged pusher and return
35 it under the action of its return spring, it is necessary only
to operate the other pusher. Under the action of the
ramp *m*₁ of the notch *m* of the said other pusher, the ball
is forced transversely to disengage the head of the en-
gaged pusher and cause its release, the latter returning to
40 its retracted position under the action of the spring *f* until
the head of its pusher engages the upper part of the cap *c*.
Further movement of the head of the pusher correspond-
ing with the new color locks the ball point therefor in
the writing position.

45 It will be noted that the small number and simplicity of
the components of the pen are conducive to manufacture
at unusually low cost.

The invention may be embodied in other specific forms
without departing from the spirit or essential character-
50 istics thereof. The present embodiment is therefore to
be considered in all respects as illustrative and not re-
strictive, the scope of the invention being indicated by the
 appended claims rather than by the foregoing description,
 and all changes which come within the meaning and range
 55 of equivalency of the claims are therefore intended to be
embraced therein.

The invention claimed is:

1. A writing device comprising a casing; a plurality of
elongated writing units; said writing units being mounted
60 in said casing for axial movement along the axis of said
casing and being separately movable between a writing
position and a retracted position in said casing; spring
means biasing each writing unit to its retracted position
in said casing; abutment means fixed longitudinally relative
65 to said casing and positioned between said writing
units; locking means on each of said writing units engageable
by said abutment means when said writing units are
moved into their writing positions for restraining said
units against retraction by said spring means; a spherical
70 member; guide means fixed relative to said casing and
positioned between said writing units; said spherical mem-
ber being supported by said guide means and being ca-

pable of movement transversely with respect to the longitudinal axis of said casing; and camming means integrally formed on each writing unit; the camming means of one of said writing units cooperating directly with said spherical member upon movement of said one writing unit from its retracted position toward its writing position to force said spherical member against another of said writing units when the latter is in its writing position and to move the locking means of said other writing unit clear of said abutment means so as to cause a spring-biased retraction of said other writing unit to its retracted position.

2. A writing device as defined in claim 1 wherein said abutment means and said guide means form parts of a unitary structure which is fixed longitudinally relative to said casing and positioned between said writing units.

3. A writing device as defined in claim 2 wherein said guide means is comprised of an aperture in said unitary

structure, which aperture extends completely through said unitary structure in a direction transverse to the longitudinal axis of said casing; said spherical member being positioned in said aperture.

5. A writing device as defined in claim 3 wherein each of said writing units is provided with a recess one wall of which serves as said camming means; said spherical member being movable at least partially into the recess of one of said writing units in its retracted position when another of said writing units is moved from its retracted position toward its writing position.

10 6. A writing device as defined in claim 4 wherein said writing units are ball-point pens.
